UNITED STATES PATENT OFFICE.

MOSES SOLOMON OKUN, OF NEW YORK, N. Y.

CENTRIFUGAL PUMP.

1,262,240.

Specification of Letters Patent. Patented Apr. 9, 1918.

Application filed June 15, 1912, Serial No. 702,918. Renewed July 4, 1917. Serial No. 178,521.

To all whom it may concern:

Be it known that I, MOSES S. OKUN, citizen of the United States, and resident of New York city, in the county of New York and State of New York, have invented certain new and useful Improved Centrifugal Pumps, of which the following is a specification.

My invention belongs to the class of apparatus which is known under the name:—centrifugal pumps. It is the object of my invention to construct a centrifugal pump which will occupy a small space and which is simple, light, efficient, and will pump large masses of liquid or fluid. Another object of my invention is to overcome the vast amount of the skinfriction of the liquid around the walls of the cylinder or casing. The skinfriction developed in such cases increases more than proportionally to the square of the revolutions of the impeller.

To attain such results I provide means in my apparatus to interpose a body of liquid in the space between the impeller and the walls of the cylinder or casing. Such body of liquid will reduce or entirely prevent the skinfriction of the liquid discharged from the impeller, while the same is speeding around the walls of the cylinder or casing. To this end my invention consists in the various novel and peculiar arrangements and combinations of several parts of the apparatus all as hereinafter fully described and then pointed out in the claims.

My invention is illustrated in the accompanying drawings, where Figure 1 represents a cross-sectional view of my invention, Fig. 2 a longitudinal sectional view of the same, Fig. 3 shows in reduced scale a top view of my invention, Fig. 4 shows a side plan view of my invention used as an air blower, Fig. 5 shows my apparatus used in combination with a jet propeller for the purpose of the propulsion of ships.

Referring to the drawing in which like numbers of reference designate like parts throughout, 1 is a shaft provided with the pulley 2; 3, 3, are shaft-holders for the shaft 1. 4 is a rotating body mounted on the shaft 1 and which is provided in both sides with blades or projections 5, 5; 6, 6, are passages formed by the said blades, 8 and 9 are pipes supplying water to the middle of both sides of the rotating body 4, 10 is a water pipe connecting both pipes 8 and 9; 11 is a valve for regulating the amount of

water supplied to the pump by the pipe 10; by closing the valve 11 the supply of water to the apparatus is cut off. 7 is casing in which the body 4 rotates, 7', 7' are the sides or the covers of the casing 7, 12 is a space between the body 4 and the inner periphery of the casing 7; 13, 13 are openings in the sides 7', 7' of the casing 7 through which water is supplied to the middle of both sides of the rotating body 4; 13', 13' is the spaces formed on both sides of the rotating body 4 in the center between the sharp sides of the blades 5; 14 is a water-pipe through which water is supplied into the space 12 between the 70 casing 7 and the rotating body 4, 15 is a valve by means of which the supply of water through the pipe 14 could be regulated or cut off entirely if desired. 16 is the discharge channel through which the water is discharged from the pump, 16' is the space in the channel 16, 17 is a partition for the purpose of preventing water from entering directly into the discharge channel 16 from the water pipe 14; 18 is another water supply pipe from which the water enters directly into the discharge channel 16 together with the water discharged from the space 12 of the apparatus, 19 is a valve by means of which the supply of water through the pipe 85 18 could be regulated or entirely cut off if desired, 20 is a pressure tank into which the water discharged from the pump may be forced in through the channel 16, 21 is a water pipe through which the water is discharged from the pressure tank 20, 22 is a valve for the pipe 21, 23 is the base for the pump.

I prefer to have the cross-sectional area of the discharge channel 16' gradually increasing from one end to the other 20, so as to have the larger cross-sectional area of the discharge-channel connected with the pressure tank. The apparatus shown in Fig. 4 is adapted for use as an air blower. The air 100 is admitted into the apparatus through the opening 13, 13 in the sides 7', 7' of the casing 7. The slot or passage 24 admits the air into the space 12 between the casing and the rotating body 4, 16 is the discharge channel. 105 Fig. 5 shows a method by which my invention can be used for the purpose of propelling ships. 26 is a boat which is propelled by my invention. The water is taken in by the centrifugal pump and is forced by the same 110 into the pressure tank 20, which is fastened to the boat 26, the said tank 20 is provided

at the bottom with the discharge vanes 25, through which the water is discharged outside. This will exercise considerable pressure upon the boat and will propel the same.

5 The operation of my apparatus is about as follows:—The shaft 1 and the body 4 is driven by a belt or in some other manner in the direction indicated by the arrows. The liquid or fluid is drawn into the space 13', 10 13' through the openings 13, 13 and pipes 8, 9 and 10, or directly through the openings 13, 13 as in Fig. 4. Said liquid or fluid will pass through the channels 6 and will be put in rapid rotary motion by the blades 5.

15 After being forced out from the channels 6, 6, 6 by centrifugal force, the liquid or fluid will continue its motion in the same direction around the inner periphery of the walls of the casing 7 until the same will be 20 discharged from the apparatus through the discharge channel 16. When it is desired to increase the amount of liquid or fluid pumped by my apparatus, the valve 15 is opened and another stream of liquid or fluid is admitted 25 through the pipe or channel 14 as in Fig. 1, or through the slot 24 as in Fig. 4 into the space 12 between the inner side of the casing 7 and the rotary body 4 of the apparatus.

The liquid or fluid forced through the 30 channels 6, will, on account of its high velocity, put in motion the stream of liquid or fluid admitted directly into the space 12. Both of these streams will then move together in the same direction around the 35 periphery of the walls of the casing 7 until discharged through the channel 16.

If it is desired to increase still more the amount of liquid pumped by my apparatus, the valve 19 is opened and another stream 40 of liquid is introduced through the pipe 18 into the discharge channel 16.

The liquid discharged from the apparatus through the discharge channel 16 will draw in liquid through the pipe 18. I wish to be 45 understood as not limiting my invention to the precise forms of construction herein set forth, as various modifications may be made in the different parts thereof without, however, departing from the spirit of my invention.

50 Having thus described my invention, what I claim, and desire to secure by Letters Patent, is—

1. A centrifugal pump comprising an impeller located and adapted to rotate within a casing or cylinder at a certain distance from the walls of the same, so as to form a chamber between the impeller and said casing, means to supply one stream of liquid or 55 fluid into said chamber and another separate stream to the said impeller, means provided in the impeller to drive the liquid or fluid with a certain velocity from the middle of the same outwardly, so as to set in motion 60 the liquid or fluid in the chamber around the 65

impeller, a discharge channel connected with the casing to discharge the liquid or fluid from the pump, substantially as described.

2. A centrifugal pump comprising an impeller located and adapted to rotate within 70 a casing or cylinder at a certain distance from the walls of the same, so as to form a chamber between the impeller and said casing, means to supply liquid or fluid into said chamber, channels provided in the impeller 75 to drive with a certain velocity a stream of liquid or fluid from the middle of the casing to the outside of the same, whereby the liquid or fluid in the said chamber is set in motion by the liquid or fluid discharged from the 80 impeller, a discharge channel connected with the said chamber to discharge the liquid from the pump, substantially as described.

3. A centrifugal pump comprising an impeller located and adapted to rotate within 85 a casing or cylinder, so as to form a chamber between said casing and the impeller, said chamber being provided at one end with a cover or partition, the other end of the chamber being terminated into a discharge channel 90 through which the liquid or fluid is discharged from the pump, means to supply liquid or fluid into said chamber, blades or paddles provided in the impeller to drive with a certain velocity a stream of liquid or 95 fluid from the middle of the casing to the outside of the chamber, whereby the liquid or the fluid in the chamber is set in motion by the liquid discharged from the impeller, substantially as described. 100

4. A centrifugal pump comprising a casing in which a body adapted to have a rotary motion is mounted, means to supply liquid or fluid into the middle of said casing, a space between the casing and the said body, 105 means provided by the said body to force the liquid or fluid with a certain velocity into said space, means to supply another stream of liquid or fluid into the same space and a discharge pipe or channel through 110 which the liquid or fluid is discharged from the pump, substantially as described.

5. A centrifugal pump comprising a casing in which a body is mounted adapted to have a rotary motion, said body being provided with paddles or blades spaced between the said body and the casing, means to supply liquid or fluid into the middle of said casing, said liquid or fluid being forced with a certain velocity into the said space, means 115 to supply another stream of liquid or fluid into the same space and a discharge pipe or channel to discharge the liquid or fluid from the pump, substantially as described.

6. A centrifugal pump comprising a casing in which a body adapted to have a rotary motion is mounted, said body being provided with paddles or blades, a space between said body and the casing, means to supply liquid or fluid into said space, means 120 to supply another stream of liquid or fluid into the same space and a discharge pipe or channel to discharge the liquid or fluid from the pump, substantially as described. 125

- to supply another stream of liquid or fluid into the middle of the casing, a discharge channel through which the liquid or fluid is discharged from the pump and a supply 5 pipe or channel connected with the discharge and which supplies a third stream of liquid or fluid into said discharge channel, substantially as described.
7. A centrifugal pump comprising a casing in which a body adapted to have a rotary motion is mounted, means to supply liquid or fluid into the middle of said casing, a space between the said casing and the said body, means provided by the said body to 10 force the liquid or fluid from the middle of the casing with a certain velocity into the said space, a pipe or channel supplying another stream of liquid or fluid into the same space, a discharge channel through which 15 the liquid or fluid is discharged from the pump, a partition to separate said supply channel from the discharge, substantially as described.
8. A centrifugal pump comprising a casing 20 in which blades or paddles are mounted upon a shaft and adapted to have rotary motion, the opposite sides of the blades forming an angle, so as to have the thickness of the said blades gradually enlarged in the 25 direction from the shaft to the outside, a space between the blades and the shaft, means to introduce liquid into said space, another space between the outside of the 30 blades and the inside periphery of the casing, means to introduce a second stream of liquid into the space between the casing and the outside of the blades, and a discharge channel through which the liquid is 35 discharged from the pump, substantially as described.
9. A centrifugal pump comprising a casing 40 in which blades or paddles are mounted upon a shaft and adapted to have rotary motion, the opposite sides of the blades form an angle, so as to have the thickness of said 45 blades or paddles gradually increased in the direction from the shaft to the outside of the blades, means to introduce liquid into the middle of the casing, a space between the outside of the 50 blades and the casing, means to introduce a second stream of liquid into the said space between the casing and the blades and a discharge channel or pipe to discharge 55 the liquid from the pump, substantially as described.
10. A centrifugal pump comprising an impeller located and adapted to rotate within a casing or cylinder at a certain distance from the walls of the same, so as to form a 60 chamber between the impeller and the casing, means to supply one stream of liquid or fluid into said chamber and another separate stream to the said impeller, means to regulate the supply of liquid or fluid to the impeller, means provided in the impeller to 65
- drive the liquid or fluid with a certain velocity from the middle of the same outwardly, so as to set in motion the liquid or fluid in the chamber around the impeller, a discharge channel to discharge the liquid or fluid from the pump, substantially as described.
11. A centrifugal pump comprising an impeller located and adapted to rotate within a casing or cylinder at a certain distance from the walls of the same, so as to form a chamber between the impeller and said casing, means to supply one stream of liquid or fluid into said chamber and another separate stream to the said impeller, means to regulate the supply of liquid or fluid to the impeller, means to regulate the supply of liquid or fluid into the chamber, means provided in the impeller to drive the liquid or fluid with a certain velocity from the middle of the same outwardly, so as to set in motion the liquid or fluid in the chamber around the impeller, a discharge channel to discharge the liquid or fluid from the pump, substantially as described.
12. A centrifugal pump comprising a cylinder or casing, an impeller adapted to rotate within said casing, means to supply liquid or fluid to the middle of said impeller, straight channels provided in the same to drive the liquid or fluid from the middle of the said impeller outwardly, a space within the inclosure formed between the impeller and the surrounding wall of the casing into which the liquid is discharged with a certain velocity from the impeller, means to introduce another stream of liquid or fluid into said inclosure and a discharge channel through which the liquid or fluid is discharged from the pump.
13. A centrifugal pump comprising a cylinder or casing, an impeller adapted to rotate within said casing and which is provided with straight channels of uniform cross-sectional area extending from the middle of the same outwardly, a space between the impeller and the surrounding wall of the casing into which the liquid is discharged with a certain velocity from the impeller, means to introduce a second stream of liquid into said space, a discharge channel through which the liquid is discharged from the pump, a partition to separate the discharge stream from the inlet stream.
14. A centrifugal pump comprising an impeller located within a cylinder or casing and adapted to rotate therein, said impeller being situated at a certain distance from the walls of the casing, so as to form a chamber between the casing and the impeller, means to supply liquid or fluid to the impeller, means provided in the impeller to drive the liquid outwardly into said chamber, means to interpose into said chamber a stream of liquid into the space between the casing and the liquid discharged from the impeller, so

as to prevent or to reduce the skin friction of the liquid discharged from the impeller while said liquid is moving around in the said chamber, a discharge channel to discharge the liquid from the pump, substantially as described.

15. A centrifugal pump comprising an impeller adapted to rotate and which is located within a cylinder or casing at a certain distance from the walls of the same, so as to form a chamber between the impeller and the said casing, means to supply one stream of liquid or fluid into said chamber and another separate stream to the said impeller, means provided in the impeller to drive the liquid with a certain velocity outwardly whereby the liquid in the chamber is also set in

motion, a compression tank into which the liquid is forced from the pump, a diverging channel, which connects the pump and the compression tank, the narrow end of the channel being connected with the pump, while the wide end of the same is connected with the compression tank, a discharge pipe or channel to discharge the liquid or fluid from the compression tank, substantially as described.

Signed at New York in the county of New York and State of New York this 14th day of June A. D. 1912.
